UNITED STATES PATENT OFFICE.

EDWARD S. BUCKLAND, OF ENDICOTT, NEW YORK.

DESIGN FOR A CLOCK.

43,733.

Specification for Design.

Patented Mar. 25, 1913.

Application filed March 16, 1912. Serial No. 684,338. Term of patent 14 years.

To all whom it may concern:

Be it known that I, EDWARD S. BUCKLAND, a citizen of the United States, residing at Endicott, in the county of Broome and State of New York, have invented a new, original, and ornamental Design for Clocks, of which the following is a specification, reference being had to the accompanying drawings, forming a part thereof, in which—

The figure is a perspective view.

I claim:—

The ornamental design for a clock, as shown.

In testimony whereof I affix my signature in presence of two witnesses.

EDWARD S. BUCKLAND.

Witnesses:

G. H. NICHOLS,
M. D. CARLETON.

Copies of this patent may be obtained for five cents each, by addressing the "Commissioner of Patents, Washington, D. C."
